UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. **7,912**, dated December 1, 1874; application filed November 19, 1874.
[Term of Patent 14 years.]

CASE B.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the casing of a soda-water apparatus, which is of rectangular form, and around this casing extend two bands, b b. The upper portion, c, of each of the four sides of the casing, is made orna-

mental, and terminates in a point or apex, d, an unique design being thus produced.

What I claim as my invention, and desire to secure by Letters Patent, is—

The design for the casing of a soda-water apparatus, substantially as herein shown and described.

Witness my hand this 16th day of November, A. D. 1874.

GEO. F. MEACHAM.

In presence of—

P. E. TESCHEMACHER,
G. A. MEACHAM.
